UNITED STATES PATENT OFFICE

CHARLES A. PRATT, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed December 19, 1928, Serial No. 326,973. Renewed February 18, 1931.

This invention relates to improvements in mining machines and has for its principal object to provide a means for deflecting the cuttings from the path of the cutter bar in a machine of the arcwall or slabbing type adaptable to cut at or near the mine bottom.

Heretofore, machines of the slabbing or arcwall type have been provided with a depending cutter bar which cuts at or near the mine bottom. Such cutter bars deposit cuttings on the mine floor which accumulate in large quantities ahead of the cutter bar. This accumulation of cuttings greatly retards the progress of said cutter bar as it is cutting along the coal face in that the cutter chain has to cut through the loose cuttings discharged from said cutter chain which increases both the load on the cutter chain and the power required to feed the cutter bar across the coal face. This slows down the speed of cutting, and requires the use of more power than would be necessary if a means were provided to clear the cuttings from the advance side of the cutter bar.

Prior to my invention, the only means of removing the cuttings from ahead of the cutter bar was by hand shoveling. This has proved to be a very dangerous and impractical method of removing said cuttings due to the close proximity of the shoveler to the cutter bits and due to the fact that the cutter chain discharges the cuttings from the kerf faster than can be handled by one man and the additional fact that there is usually insufficient room for two men to safely work ahead of said cutter bar.

The purpose of my invention is to provide a guide means on the advance and rearward side of the cutter chain through which the cuttings may be moved by the cutter chain and expelled on the retreating side of the machine, thus eliminating the use of man power to perform the operation.

My invention may be more clearly understood with reference to the following drawings wherein:

Figure 1 is a top plan view of a mining machine of the slabbing type making a cut in a mine wall having my invention embodied thereon;

Figure 2 is an enlarged fragmentary plan view of a mining machine of the slabbing type showing the details of my invention;

Figure 3 is an enlarged fragmentary side elevation of the mining machine shown in Figure 1 cutting a kerf in a mine wall above the mine bottom and having the device embodying my invention thereon;

Figure 4 is an enlarged fragmentary side elevation of the mining machine shown in Figure 1 cutting a kerf in a mine wall along the mine bottom having the device embodying my invention thereon;

Figure 5 is a sectional view taken on line 5—5 of Figure 4; and

Figure 6 is a sectional view taken on line 6—6 of Figure 3 with parts broken away to more clearly show the details of my invention.

In the embodiment of my invention as illustrated, my invention is shown as applied to a mining machine 1 of the slabbing type which is adapted to cut a kerf in a mine wall at the mine bottom or at various elevations with respect to said mine bottom. The mining machine herein illustrated is similar to that shown in an application bearing Serial Number 157,005 filed by William T. McCullough, December 25, 1926, and will not herein be described in detail excepting as to parts which pertain particularly to my invention, and comprises a wheeled truck 2 having a turntable 3 thereon which turntable in turn has a cutting element 4 trunnioned thereon near the forward portion of said turntable.

The cutting element 4 has a cutter head 5 depending therefrom and vertically adjustable with respect thereto in guides 6—6. A threaded shaft 7 driven by a motor 8 on the rearward portion of the cutting element 4 in a suitable manner not herein described is provided to move the cutter head 5 in the guides 6—6. A cutter bar 9 extends longitudinally forward from the cutter head 5 and is provided with guides 10 for receiving a cutter chain 11 which is movable thereabout. The cutter chain 11 is driven by a sprocket 12 from the motor 8, in its various positions of adjustment with respect to the cutting ele-

ment through a suitable gear train which will not herein be described since it is no part of my invention.

Referring now more particularly to the novel feature of my invention, an arcuate guide 15 depends from the cutter head 5 to the mine bottom when the cutter bar 9 is making a normal cut along the mine bottom, and is integral with said cutter head. The arcuate guide 15 extends rearwardly from the forward portion of the cutter head 5 on the advancing side of the machine around the rearward portion of the cutter chain 11 and sprocket 12 and opens to the retreating side 15 of said machine as is illustrated in Figure 2.

An adjustable deflector 16 overlaps a portion of the arcuate guide 15 and extends forwardly therefrom along the cutter bar 9 to a point adjacent the face of the coal during a normal cutting operation. The deflector 16 is vertically adjustable so as to engage the mine bottom when the cutter bar 9 is cutting on the mine bottom or above said mine bottom, and is supported on a plurality of bolts 17-17 having nuts thereon which are slidable in guides 18, 18, in a member 19 attached to a cutter bar supporting member 20 by any suitable means in a manner well known to the art, as for instance, rivets or nuts and bolts. A plurality of connecting links 25, 25, connect the end bolts 17, 17, with levers 26, 26, fixed on the outer ends of transversely disposed shafts 27 and 28 journaled on the top portion of the member 19, the forward lever 26 being fixed on the shaft 27 and the rearward lever 26 being fixed on the shaft 28. The forward and rearward levers 26 are connected together by means of levers 29, 29, fixed on the respective shafts 27 and 28 at right angles to the levers 26, 26, and connected together at their outer extremities by means of a connecting rod 30.

A hand lever 31 is fixed on the shaft 28 at right angles to the lever 26 to move the levers 26, 26, about their axes and thus to raise or lower the adjustable deflector 16 through the connecting links 25, 25. A sector plate 32 projects upwardly from the member 19 and has a plurality of holes 33, 33, therein. A pin 34 is adaptable to pass through a hole in the hand lever 31 and any one of the holes 33 in the sector plate 32 to hold the hand lever 31 in a fixed position with respect to said sector plate and thus hold the adjustable deflector 16 in a fixed position with respect to the cutter bar 9 so said deflector may be held in engagement with the mine bottom when said cutter bar is at various heights with respect to said mine bottom.

From the foregoing description it will be seen that when the deflector 16 and the arcuate guide 15 are in engagement with the mine bottom, a continuous cuttings passageway from the mine face to the discharge or retreating side of the cutter head 5 is formed

which is closed on the advance side of the machine and open on the retreating side of the machine. With this arrangement, when the cutter bar 9 is cutting a kerf in the coal face movement of the cutter chain 11 about the cutter bar 9 will move the cuttings through said passageway and eject said cuttings from the side of the machine opposite to which the entire machine is moved during the cutting operation, and that no cuttings can get into the path of movement of the cutter head 5 or cutter bar 9.

It may also be seen that when the cutter bar 9 is cutting above the mine bottom, as for instance when the cutter bar is cutting out a band of impure coal or dirt at the bottom of the coal seam, and it is desired to cut into said impurities just below said coal seam that the adjustable deflector 16 (see Figure 3) may engage the mine bottom to prevent the cuttings from getting in the path of the cutter head 5 or cutter bar 9, and the arcuate guide 15 will guide said cuttings so they may be expelled at the retreating side of the cutter head 5 beyond the path of said cutter head.

Although I have shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated in the drawings, excepting as it may be limited by the appended claims.

I claim as my invention:

1. In combination with a truck mounted mining machine having a depending cutter head, a cutter bar projecting forwardly therefrom and adapted to cut a kerf adjacent the mine bottom, and means for expelling the cuttings discharged from said cutter bar beyond said machine on the retreating side thereof comprising a closure member closing the advance side of the machine from a point substantially adjacent the mine face when said cutter bar is sumped thereunder thence rearwardly along said cutter bar and around the rearward end thereof opening to the retreating side of said cutter bar.

2. In combination with a truck mounted mining machine having a depending cutter head, a cutter bar projecting forwardly therefrom and adapted to cut a kerf along a mine bottom, a cutter chain movable about said cutter bar, and means cooperating with said cutter chain for expelling the cuttings discharged from said cutter chain beyond said machine on the retreating side thereof comprising a closure member closing the advance side of the machine from a point substantially adjacent the mine face when said cutter bar is sumped thereunder, thence rearwardly along said cutter bar and around the

- rearward end thereof opening to the retreating side of said cutter bar and forming a passage from the mine face along the advance side of said cutter bar to the rearward side thereof so that movement of said cutter chain rearwardly along said cutter bar may move the cuttings through said passageway and eject said cuttings beyond said cutter bar on the retreating side thereof.

3. In combination with a truck mounted mining machine having a depending cutter head, a cutter bar projecting forwardly therefrom and adapted to cut a kerf along a mine bottom, a cutter chain movable about said cutter bar, and means cooperating with said cutter chain for expelling the cuttings discharged from said cutter chain beyond said machine on the retreating side thereof comprising a vertically adjustable deflector extending along the advance side of said cutter bar for a portion of its length, and an arcuate guide depending from said cutter head and extending from the rearward portion of said adjustable deflector around the rearward portion of said cutter bar to the retreating side thereof.

4. In combination with a truck mounted mining machine having a depending cutter head, a cutter bar projecting forwardly therefrom and adapted to cut a kerf along a mine bottom, means for vertically moving said cutter head so said cutter bar may cut at various elevations with respect to a mine bottom, a cutter chain movable about said cutter bar, and means cooperating with said cutter chain for expelling the cuttings discharged from said cutter chain beyond said machine on the retreating side thereof comprising a vertically adjustable deflector on the advance side of said cutter bar extensible from a portion above said cutter bar to the mine bottom when said cutter bar is cutting a kerf in the mine wall along the mine bottom or at a point above said mine bottom and an arcuate guide depending from said cutter head to the mine bottom when said cutter bar is cutting along the mine bottom and extending rearwardly around the rearward portion of said cutter bar to the retreating side thereof.

5. In combination with a truck mounted mining machine having a depending cutter head, a cutter bar projecting forwardly therefrom and adapted to cut a kerf along a mine bottom, means for vertically moving said cutter head so said cutter bar may cut at various elevations with respect to a mine bottom, a cutter chain movable about said cutter bar, and means cooperating with said cutter chain for expelling the cuttings discharged from said cutter chain beyond said machine on the retreating side thereof comprising a member extending outwardly from above the top portion of said cutter bar on the advance side thereof, and a vertically adjustable cut-

tings deflector extensible from said member vertically downward to the mine bottom when the cutter bar is cutting along the mine bottom or above said mine bottom.

6. In combination with a truck mounted mining machine having a depending cutter head, a cutter bar projecting forwardly therefrom and adapted to cut a kerf along a mine bottom, means for vertically moving said cutter head so said cutter bar may cut at various elevations with respect to a mine bottom, a cutter chain movable about said cutter bar, and means cooperating with said cutter chain for expelling the cuttings discharged from said cutter chain beyond said machine on the retreating side thereof comprising a member extending outwardly from above the top portion of said cutter bar on the advance side thereof, and a vertically adjustable cuttings deflector extensible from said member vertically downward to the mine bottom when the cutter bar is cutting along the mine bottom or above the mine bottom, and a means for vertically moving said cuttings deflector with respect to said outwardly extending member.

7. In combination with a truck mounted mining machine having a depending cutter head, a cutter bar projecting forwardly therefrom and adapted to cut a kerf along a mine bottom, means for vertically moving said cutter head so said cutter bar may cut at various elevations with respect to a mine bottom, a cutter chain movable about said cutter bar, means cooperating with said cutter chain for expelling the cuttings discharged from said cutter chain beyond said machine on the retreating side thereof comprising a member extending outwardly from above the top portion of said cutter bar on the advance side thereof, a vertically adjustable cuttings deflector extensible from said member vertically downward to the mine bottom when the cutter bar is cutting along the mine bottom or above the mine bottom, means for vertically moving said cuttings deflector with respect to said outwardly extending member, and an arcuate guide extending from said vertically adjustable cuttings deflector rearwardly around the rearward portion of said cutter bar to the retreating side thereof and depending from said cutter head to the mine bottom when said cutter bar is cutting along the mine bottom.

8. In combination with a truck mounted mining machine having a depending cutter head, a cutter bar projecting forwardly therefrom and adapted to cut a kerf adjacent the mine bottom, and means for expelling the cuttings discharged from said cutter bar beyond said machine comprising a vertically adjustable deflector extending along said cutter bar.

9. In combination with a truck mounted mining machine having a depending cutter

head, a cutter bar projecting forwardly therefrom and adapted to cut a kerf adjacent the mine bottom, and means for expelling the cuttings discharged from said cutter bar beyond said machine comprising a vertically adjustable deflector extending along the advance side of said cutter bar.

10. In combination with a truck mounted mining machine having a depending cutter

10 head, a cutter bar projecting forwardly therefrom and adapted to cut a kerf adjacent the mine bottom, a cutter chain movable about said cutter bar, and means cooperating with said cutter chain for expelling the cuttings discharged from said cutter chain beyond said machine on the retreating side thereof comprising a deflector extending along the advance side of said cutter bar for a portion of its length and thence rearwardly around the rearward end of said cutter bar and opening to the retreating side thereof rearwardly of said cutter chain.

15 Signed at Chicago, in the county of Cook and State of Illinois, this 10th day of December, A. D. 1928.

CHARLES A. PRATT.
